BOX WRAPPING SYSTEM

Filed April 8, 1926

Box is placed on form block structure and cycle of machine begins here.

Pin in top of plunger meets auxiliary lever at this point causing upper & middle form blocks to separate.

5 Sheets-Sheet 5

Box is stripped from form block at this point.

UNITED STATES PATENT OFFICE.

JOHN R. SONNEBORN, OF WILLOW GROVE, PENNSYLVANIA, ASSIGNOR TO STOKES AND SMITH COMPANY, OF PHILADELPHIA, PENNSYLVANIA, A CORPORATION OF PENNSYLVANIA.

BOX-WRAPPING SYSTEM.

Application filed April 8, 1926. Serial No. 100,475.

My invention relates to a method, and apparatus for applying a wrapper, sheet, label or the like, hereinafter generically termed "a wrapper" to a box, box structure, package, container structure or the like, herein-after generically termed a "box".

In accordance with my invention, engagement of the box-bottom and a section of the wrapper having been properly effected, a portion of a wrapper side panel is folded into engagement with the horizontal surface of a box end wall and thereafter another portion of the side panel aforesaid is folded into engagement with the horizontal surface of a box side wall meeting said end wall in a corner.

Further in accordance with my invention, engagement of the box bottom and a section of the wrapper having been effected, as aforesaid, a portion of a wrapper side panel is folded into engagement with the horizontal surface of a box end wall whereupon a corner-lap section comprised in said side panel is folded into engagement with the vertical surface of said end wall and, preferably, during the operation last mentioned the upper portion or extremity of the corner-lap section after being subjected to a creasing operation or the like remains temporarily upstanding from which position it is bent or folded and finally assumes a position beneath a portion of the turn-in section of a wrapper end panel as said turn-in section is brought into adhering relation with the upper horizontal surface of the box end aforesaid.

Further in accordance with my invention, to a box having side and end walls meeting in a corner and which rise, respectively, different distances from the box-bottom there is applied a wrapper and after a portion of a wrapper side panel has been folded into engagement with the horizontal surface of the box end wall aforesaid, the panel is slit or cut in a direction extending toward the box-bottom, and more particularly, the folding and slitting operation aforesaid is performed substantially simultaneously.

Further in accordance with my invention, portions of a wrapper are caused to overlie and adhere to the horizontal surfaces of the

walls of a box by a wiping or ironing action.

Further in accordance with my invention, to the portions of a wrapper freshly folded into engagement with the interior surfaces of the box walls there is applied pressure effective from one or more regions within the box for causing intimate engagement between the box walls and wrapper portions aforesaid.

Further in accordance with my invention, the box-wrapping or covering operation is effected automatically in a wrapping machine or the like whose corner-lap mechanism comprises structure for folding a portion of a wrapper into engagement with the horizontal surface of a box wall and for slitting or cutting the wrapper in a direction extending toward the box-bottom.

Further in accordance with my invention, in a wrapping machine as aforesaid there is included novel structure for causing the various turn-in sections of a wrapper to assume horizontal positions above the box walls and bottom, and more particularly, the structure aforesaid wipes or irons portions of the wrapper into engagement with horizontal surfaces of the box walls.

Further in accordance with my invention, the form block structure of a wrapping machine is so constructed that in one position thereof pressure may be applied from directions within the box against wrapper portions freshly folded into engagement with the interior surfaces of the box walls, and more particularly, such pressure-applying mechanism comprises members movable relatively with respect to the form block structure under the influence of the automatic mechanism of the wrapping machine.

My invention resides in the method, apparatus, and features or details of construction of the character hereinafter described and claimed.

For an illustration of some of the forms my invention may take, reference is to be had to the accompanying drawings in which:

Fig. 1 is a plan view of a wrapper constructed in accordance with my invention.

Fig. 2 is a plan view of a wrapper of a modified form.

Fig. 3 is a perspective view of a box and a wrapper of the type illustrated in Fig. 1.

Figs. 4-8, inclusive, are perspective views illustrating different stages of a box-wrapping operation.

Figs. 5^a and 5^c are enlarged fragmentary perspective views showing in more detail the structure illustrated in Fig. 5.

Figs. 5^b and 5^d are enlarged fragmentary perspective views showing one stage in the application to a box of a wrapper constructed in accordance with Fig. 2.

Fig. 9 is an elevational view, partly in section, of a wrapping machine constructed in accordance with my invention.

Fig. 10 is a plan view showing a wrapping machine table and some of the wrapping instrumentalities comprised in the wrapping machine.

Fig. 11 is an elevational view of the lower part of the wrapping machine shown in Fig. 9 but looking thereat from another direction.

Fig. 12 is a chart showing the timing of various cams comprised in the wrapping machine.

Fig. 13 is an elevational view, partly in vertical section, showing one embodiment of my novel upper and intermediate form block structure together with one form of my turn-in structure.

Fig. 14 is a plan view of the turn-in structure shown in Fig. 13.

Fig. 15 is an elevational view, partly in vertical section, showing the actuating structure for the pressure-applying mechanism comprised in the upper form block.

Fig. 16 is a perspective view of form block structure constructed in accordance with my invention.

Fig. 17 is a perspective view of a corner-lap turn-in member equipped with supplementary wrapper, folding and slitting member.

Referring to Fig. 1, there is illustrated a wrapper W of suitable material, as paper. It is to be understood that ordinarily wrapper W is a plane flat sheet, cut and notched as indicated, but unscored and uncreased. For purposes of explanation, however, the wrapper is shown as traversed by a plurality of broken lines apparently effecting division thereof into a number of sections.

Accordingly, and as herein shown, the broken lines aforesaid may be assumed to divide wrapper W into a bottom section a and the oppositely disposed end panels b, each of the latter comprising a turn-in section b¹, each turn-in section in turn comprising a portion b² adapted to lie along the top horizontal surface of one end of the box and a portion b³ adapted to be folded within the box end, the vertical dimension or width of the extremity of portion b³, as viewed in Fig. 1, being somewhat less than the corre-

sponding vertical dimension of the end panel proper. Also, wrapper W may be assumed to comprise the front side panel c and the rear side panel d. Front side panel c comprises the turn-in section c¹, said turn-in section comprising a portion c² adapted to lie along the top horizontal surface of the front wall of the box and a portion c³ adapted to be folded into engagement with the upper interior surface of said front wall of the box. Front side panel c also comprises the generally rectangular sections c⁴ adapted, respectively, to overlie and adhere to portions of the top horizontal surfaces of the end walls of the box at the front thereof, as hereinafter more fully described. Front side panel c also comprises the corner lap sections c⁵, each of the latter in turn comprising a generally rectangular section c⁶ adapted to be folded into engagement with and in part overlie one of the rectangular sections c⁴ aforesaid and the contiguous area of the top horizontal surface of the end wall of the box receiving said section c⁴.

Rear side panel d comprises the turn-in sections d¹, each of the latter comprising a section d² adapted to lie along a portion of the top horizontal surface of the rear wall of the box and a section d³ adapted to be folded into engagement with the interior surface of said rear wall of the box. Panel d also comprises the generally rectangular sections d⁴ adapted, respectively, to overlie and adhere to portions of the top horizontal surfaces of the end walls of the box at the rear of the box, as hereinafter more fully described. Panel d also comprises the corner lap sections d⁵, each of the latter comprising a generally rectangular section d⁶ adapted to be folded into engagement with and in part overlie one of the rectangular sections d⁴ aforesaid and the contiguous area of the top horizontal surface of the end wall of the box receiving said section d⁴. It will be observed that turn-in sections d¹, in part, are formed, in the example shown, by eliminating a rectangular section from the rear side panel d. As a result a portion of the rear wall of the box remains uncovered by the wrapper.

In Fig. 2, I have illustrated a modified form of wrapper W¹ generally the same as that shown in Fig. 1, differing, however, in that the rectangular sections c⁴ comprised in the front panel c are each notched as indicated at c⁷, the notches preferably converging toward the center of the wrapper. Likewise, the rectangular sections d⁴ comprised in the rear panel d are similarly notched as indicated at d⁷, these notches also preferably converging toward the center of the wrapper.

Wrappers of the character aforesaid may be coated with adhesive of a desired character in any suitable manner and should be ap-

plied to the box before material hardening or setting of the adhesive coating. As one manner of effecting the wrapping operation, I have indicated in Fig. 3 a coated wrapper W ready for application to a box B which, for the sake of clarity, may be arbitrarily assumed to comprise the bottom B¹, end walls B², front wall B³ and rear wall B⁴. As shown, front and rear walls B³ and B⁴ are of less height than are the end walls, the differences in height preferably being of such magnitude that when the box lid is fitted between end walls B², the upper surface thereof will lie flush or in the same plane with the top faces of said end walls B².

Initially, engagement is effected between bottom B¹ of box B and section a of wrapper W. Thereafter, front side panel c of wrapper W is folded into engagement with front wall B³ or box B and rear side panel d of said wrapper is folded into engagement with rear wall B⁴ of the box. The condition of the combined structure in this stage of the operation is indicated in Fig. 4.

Corner lap sections c¹ are now folded into engagement, respectively, with end walls B² of box B, whereupon rectangular sections c² of front side panel c are bent downwardly into adhering relation, respectively, with the top horizontal surfaces of the box end walls B² at the front of the box, and by a suitable creasing operation, the rectangular sections c² of corner lap sections c¹ are left upstanding as indicated in Figs. 5 and 5^a. Preferably simultaneously with the folding and creasing operation aforesaid, the wrapper is cut or slit along the parallel lines x, Fig. 1, thereby completing the formation of turn-in section c¹, the depth of these cuts below the rectangular sections c² usually corresponding generally with the difference in height between end walls B² of box B and its adjacent front wall B³.

Corner lap sections d¹ are likewise folded into engagement, respectively, with end walls B² of the box, whereupon rectangular sections d² are folded downwardly into adhering relation, respectively, with the top horizontal surfaces of the box end walls B² at the rear of the box, Figs. 5 and 5^a, and again by a suitable creasing operation the rectangular sections d² of corner lap sections d¹ are left upstanding. Also, preferably with the folding and creasing operation aforesaid, the wrapper is cut or slit along the parallel lines y, Fig. 1, thereby completing the formation of the turn-in sections d¹.

As indicated in Figs. 5^a, 6^a and 7, due to the configuration of the rear side panel d, a portion of the rear wall B⁴ of the box remains uncovered or unwrapped, whereby the hinges for the box cover may be secured in position without disturbing the wrapper.

With the combined structure in the condition indicated in Fig. 5, the next stage of the operation is effected by folding end panels b into engagement with the respective box ends, yielding the structure indicated in Figs. 6 and 6^a, whereafter the various turn-in sections b¹, c¹ and d¹ are folded into substantially horizontal position as indicated in Fig. 7. It will be observed that when turn-in sections b¹ are folded into horizontal position as aforesaid, the upstanding sections c² and d² of corner lap sections c¹ and d¹ are folded downwardly into adhering engagement, respectively, with parts of the rectangular sections c² and b¹ and the contiguous areas of the horizontal top surfaces of the box ends, for at this time the sections b² of the turn-in sections b¹ are caused to overlie the horizontal top surfaces of the box ends. It will also be observed that the section c² of turn-in section c¹ overlies the horizontal top surface of the front wall B³ of the box and that the sections d² of the turn-in sections d¹ in part overlie the horizontal top surface of the rear wall b⁴ of the box. Finally the end portions of all the turn-in sections aforesaid are folded downwardly into engagement with the inside surfaces of the various box walls to form the completed wrapped box, Fig. 8.

By the operation last noted, it will be observed that the respective notched extremities of the panel portions b² are received interiorly of the respective box end walls B² between front wall B³ and rear wall B⁴, the respective unnotched portions of said panel portions b² being of such width as to substantially completely cover those interior vertical portions of said end walls B² which extend above the top horizontal surfaces of front wall B³ and rear wall B⁴. It will also be observed that the portions b² of the respective turn-in sections b¹ substantially completely overlie the top horizontal surfaces of the respective box end walls B².

When wrapping a box of the character indicated in Fig. 3 with a wrapper as illustrated in Fig. 1, it is essential that the wrapper be cut or slit along the lines x and y during the wrapping operation. The necessity for such cutting or slitting operation arises from the fact that the box front and rear walls are of less height than are the box ends. The depth of the cuts, however, may vary within some limits, for, if insufficient, the wrapper will usually tear in the proper directions as the wrapping operation is continued.

The wrapper W¹ illustrated in Fig. 2 differs from wrapper W of Fig. 1 in that there are provided slits or notches c¹ and d¹ therein and, accordingly, the former may be applied to the box in a manner similar to that described above with respect to wrapper W except that it is unnecessary to

perform a cutting or slitting operation. In Figs. 5^b and 5^a, I have illustrated the position assumed by the notches *c'* and *d'* at one stage of the application of wrapper *W'* 5 to a box.

The foregoing wrapping operation or one equivalent therewith may be performed manually. Preferably, however, such operation is effected automatically in a wrapping 10 machine or unit of suitable type, for example, as illustrated in Figs. 9, 10, 11, 13-17, inclusive, where there is illustrated a machine or unit *M* for wrapping or covering 15 with a suitable wrapper, a box, one or more 15 of whose faces or walls is or are of substantial thickness as a cigar box or the like.

Machine *M* may be of any type suitable 20 for effecting this end, for example, of the general character disclosed in U. S. Letters 20 Patent to Smith No. 691,329, suitably modified, however, to care for the different conditions presented when wrapping a box of the kind noted above.

As herein shown in Fig. 9, machine *M* 25 comprises a base 1 from which rise the legs 2 or the like, to which in turn are secured in spaced relation the platform 3 and table 4. A standard or gooseneck 5 carried by table 4 supports a cam 6 rotated by a shaft 7, 30 which near its lower end carries a second cam 8. A worm wheel, not shown, secured to shaft 7 below cam 8, meshes with a worm 9 secured to a shaft 10 mounted in suitable bearings transversely of shaft 7. A pulley 11, 35 driven by any suitable source of power, not shown, idles on shaft 10, but may be secured thereto by a clutch 12 splined to said shaft. As well understood in the art, clutch 12 may be controlled by a lever 13 secured to a shaft 14. Upon actuation of 40 lever 13 to rotate its shaft, there is effected one cycle of operation of the wrapping machine. Also, there may be provided a lever 15 for locking the clutch in open position 45 and a lever 16 effective, when actuated, for stopping the machine at any time.

Forming a part of gooseneck 5 are the bracket arms 18 and 19, forming bearings 50 in which reciprocates a plunger 20 carrying at its lower end the spur or tenon 21 suitably secured to the middle or intermediate form block 22. The upper form block 23 overlies the intermediate form block 22, and 55 its provided with an aperture freely receiving the spur 21. A plate 24 is detachably secured to a similar plate 25 carried by the upper form block 22 in any suitable manner, as by screws 26 or the like threaded into 60 said plate 25 and received in grooves in said upper plate 24. Each of a pair of rods 27 rising from plate 24 passes, respectively, 65 through perforated lugs 28 in a plate secured to plunger 20, Fig. 16. Rods 27 pass vertically upward, and are held in proper spaced relation by a cross-head 29, Fig. 9.

Cam 6 is provided with two cam grooves *G'* and *G''*, the former receiving a roller carried by an arm 30 pivoted to an extension 31 of gooseneck 5. A link 32 is pivoted at one end of the free end of arm 30 and 70 at its other end to a yoke 33 carrying the stripper fingers 34 which, at predetermined times, pass through aligned apertures in the intermediate and upper form blocks 22 and 23 to strip the wrapped box therefrom. 75

A pair of parallel guide rods 35 are secured to yoke 33 and respectively extend upwardly through a pair of perforated lugs 36 suitably secured to plunger 20.

Groove *G''* in cam 6 receives a roller carried by an arm 37 pivoted to an extension 38 of gooseneck 5, said arm 37 at one end carrying a suitable counter weight 39 and at its other end being pivoted to an arm 40 in turn pivoted to plunger 20. 80

Extending upwardly from the base 1 are the collapsible rods or tubes 41 and 42, tube 42 sliding freely downwardly on the exterior surface of tube 41, and viewed in Fig. 9, against the expansive tendency of a coiled 90 spring 43 or the like. At its upper end tube 42 carries the platen or lower form block 44, between which and the intermediate form block 22, the box bottom and its adhering wrapper are at times confined, as 95 hereinafter more fully described.

With clutch member 12 engaged with pulley 11, cam 6 will be rotated through shaft 7, shaft 10 and the interposed gearing described above. Assuming that the intermediate and upper form blocks 22 and 23 are in their upper region of travel, rotation of cam 6 will bring cam groove *G''* into such relation with the roller on lever 37 that the descent of the intermediate and upper form 105 block structures under the influence of gravity will be permitted. Finally, a box and an adhering wrapper having been placed on the descending form block structure, it will be moved into engagement with the lower form 110 block 44, whereupon the combined form block structure comprising upper form block 23, intermediate form block 22 and lower form block 44 and the box with its wrapper move downwardly through the various instrumentalities comprised in the wrapping machine. At a predetermined time, a lug, 115 pin or projection, not shown, on cross-head 29 engages a cam, not shown, controlled by cam grooves *G'* and lever 30, to prevent further downward movement of the upper form block 23 for the time being. Immediately after downward movement of the upper form block is thus prevented, certain turn-in fingers, hereinafter described, move beneath said form block 23, whereupon the cam aforesaid is retracted from engagement with the lug or projection aforesaid, leaving form block 23 supported solely by the turn-in fingers aforesaid. Cam *G'* having performed 120

this function, now remains idle until the reform block structures begin their upward return journey, when at a proper and predetermined time cam groove G^1 functions to 5 partially rotate arm 30 in a counter-clockwise direction, as viewed in Fig. 9, to depress yoke 33 and pass the stripper fingers within the apertures in the intermediate and upper form blocks to strip or remove the 10 wrapped box therefrom.

In accordance with my invention, the upper and intermediate form blocks are constructed in a novel manner, to the end that a wrapper may be expeditiously and properly secured in adhering relation to the exterior faces of a box of the desired character. 15

Referring particularly to Figs. 13, 15 and 16, the upper form block 23, which in the example shown is preferably of metal, is 20 provided in two opposite parallel faces thereof with a channel or recess receiving an insert 45 to which a shoe 46 or the like is secured by a screw 47 or equivalent. Rising from the upper surface of form block 23, are the ears 48 or the like, pairs of which form bearings for shafts or rods 49 carrying, respectively, the form block presser members 50 comprising the upwardly extending actuating arm or lugs 51. Preferably, each presser member is biased in the direction occupied by the adjacent side of the box when on the upper form block structure 25 by a coil spring 52, or equivalent, Fig. 15.

Referring to Fig. 16, it will be observed 30 that the front face of upper form block 23 along its longer axis is provided with two presser members 50. Although not so shown, it shall be understood that the rear face thereof in parallel relation with said front face may be provided with a similar number of the presser members 50. Or, as a 35 matter of choice, any other suitable numbers of such presser members may be utilized on the front and rear faces of said form block. It will also be observed that the face of 40 form block 23 at the right, as viewed in Fig. 16, is provided with but one presser member 50. Obviously, the number of such members along said last-mentioned face of form block 23 may be varied as desired, as 45 may the number thereof along the form block face in parallel relation therewith. Likewise, it is obvious that the number or position of the actuating lugs 51 may be 50 varied as desired.

Assuming, for example, that a box of the character illustrated in Fig. 3 is to be wrapped with a wrapper of the character shown in that figure or in Fig. 1, the box 55 B is passed on to the intermediate and upper form block structure 22 and 23. Prior to the time that such form block structure is thus positioned within the box, or immediately thereafter, the section a , Fig. 1, 60 of wrapper W is caused to register with and

adhere to the bottom B^1 of the box. Thereafter, the upper and intermediate form block structures carry the bottom B^1 of the box and section a of the adhering wrapper into engagement with the lower form block 44, 70 whereupon the front and rear side panels c and d of the wrapper are folded, respectively, into engagement with the front and rear box walls B^3 and B^4 by the oppositely disposed brush structures 54 and rollers 55, 75 Figs. 9 and 10. The condition of the partially wrapped box at this stage of the operation is indicated in Fig. 4. Preferably, by the next stage of the operation, the wrapper corner-lap sections c^5 and d^5 are secured to 80 the respective box ends B^2 , the rectangular sections c^4 and d^4 of the respective front and rear wrapper panels are folded into engagement with portions of the upper horizontal surfaces of the box ends B^2 , respectively, 85 adjacent the front and rear walls of the box, and the wrapper is cut or slit along the lines x and y , Figs. 1, 5^a and 5^c. These operations may be, and preferably are, effected substantially simultaneously. 90

To this end, I may utilize a construction of the character illustrated in Figs. 9 and 11, wherein the groove G^3 of cam 8 receives a roller 56 carried by a lever 57 comprising the oppositely extending arms 58 to which, 95 respectively, are pivoted the links 59 in turn pivoted, respectively, to the members 60, each of which is secured to a shaft 61 mounted in suitable bearings carried by the bottom of table 4. At or adjacent their other ends, shafts 61 each carry a member 62 terminating, in the example shown, in a fork-shaped portion connected by a link 63 to a member 64 provided with perforations in which are received and secured the rods 65 mounted for reciprocatory movement in the slides 66. Each pair of the rods 65 terminates in a transverse member 67 on which are adjustably mounted the corner-lap members 68. 105

The construction described above for controlling corner-lap members 68 is well understood in the art. Cam 8 by its groove G^3 functions to swing lever 57, Fig. 11, in a clockwise direction at the proper time during a pause in the descent of the partially wrapped box to move the corner-lap members 68 carried by the respective members 67 toward each other along the box ends to wipe the corner-lap sections into engagement therewith. After such operations, cam groove G^3 retracts said corner-lap members 67 until such time as another box descends through the machine. 115

Suitably secured, as by the screws 69, to 120 each of the corner-lap members 68, is a U-shaped member 70, preferably of metallic spring material, one arm of which is longer than the other and whose end is upturned, as indicated at 71, Fig. 17. Formed in-

tegrally, by preference, with member 70 is the substantially plane knife-edge 72. As the various corner-lap members 68 move toward each other along the box ends to perform the wiping operation aforesaid, the knife edges 72 at each box corner, cut or slit the wrapper along the lines α and γ , Figs. 1, 5^a and 5^c, and substantially simultaneously with such cutting operation the rectangular sections c^4 and d^4 are folded into engagement with the upper horizontal surfaces of the box ends at the respective corners. Immediately adjacent such rectangular sections, the long arm of member 70 performs a creasing operation, whereby the rectangular sections c^6 and d^6 are left upstanding. The partially wrapped structure at this stage of the operation is as indicated in Figs. 5, 5^a and 5^c.

Upon completion of the foregoing operation, further movement of the form block structure is initiated, and the partially wrapped box is carried downwardly between the brushes 73 and rolls 74, Figs. 9 and 10, to fold the end panels b into engagement with the respective ends of the box, the condition of the partially wrapped structure at this stage of the operation being as indicated in Figs. 6 and 6^a.

Groove G⁴ of cam 8 receives a roller 75 carried by a lever 76 pivoted intermediate its ends to an arm 77 carried by platform 3, Fig. 9. At or adjacent its other end, lever 76 is pivoted to a link 78 in turn pivoted to a cylindrical member 79 through which passes the tube 42 carrying the lower form block 44. Member 79 comprises four radiating cylindrical arms 80 disposed ninety degrees apart around the axis of member 79. Each arm 80 carries a rod 81, from each of which rises a member 82 reciprocatory in a bearing formed in an extension 84 of slide 66. A link 83 pivoted to each member 82 is likewise pivoted to a cam 85 controlling the plates or fingers for turning the upper wrapper sections inwardly.

The construction described above for controlling cams 85 is well understood in the art. Cam 8 by its groove G⁴ functions to swing member 76 on its pivot to thereby raise members 79 and rods 81 at the proper time during another pause in the descent of the partially wrapped box for moving the turn-in fingers toward the center of the box.

In accordance with my invention, there are provided novel turn-in fingers or members for folding the turn-in sections of the wrapper inwardly into the position indicated in Fig. 7. To this end, I may utilize a construction of the character illustrated in Figs. 13 and 14, wherein each cam 85 controls one or more rods 86. Secured to the rods 86 is a member 87 to which by screw 88 are secured the plates 89 supporting the ledge 90, screws 91, respectively, securing

the plates 89 to ledge 90. Plates 89 are prevented from turning due to the fact that they engage the shoulder 87^a on member 87. Plates 89 extend in opposite direction for supporting the hinges 92, to which are attached, respectively, the turn-in fingers 93 biased in a downward direction, as viewed in Fig. 13, by leaf spring 94 or the like.

It shall be understood that four turn-in structures comprising any suitable number of pivotally mounted sections, as turn-in fingers 93, are utilized for effecting the described operation, and that two of such turn-in structures are so mounted as to move toward and from each other over the respective horizontal top surfaces of the box ends in a direction at right angles to that in which move the other two turn-in structures co-acting with the front and rear box walls. In so doing, although the ledges 90 initially engage the turn-in sections of the wrapper, the folding operation proper is performed by the turn-in fingers 93 which, due to the biasing effect of springs 94, cause wiping or ironing of the wrapper sections b^2 , c^2 and d^2 into engagement with the horizontal top surfaces of the box walls.

Ledges 90, comprised in the various turn-in structures, function primarily as a support for the upper form block 23, which, as soon as said ledges have moved into the position indicated in Fig. 13, is removed from the control of cam groove G¹ and supported solely by said ledges.

At this time, the condition of the partially wrapped structure is as indicated in Fig. 7. Cam 85 having moved the turn-in structures toward the center of the box to the full extent permitted immediately acts in a reverse direction to retract such structures, and as the ledges 90 are withdrawn from beneath the upper form block 23, that structure drops as a dead weight into the box and on to the intermediate form block 22 carrying the free portions of the now horizontally extending turn-in sections of the wrapper downwardly into adhering relation with the interior top surfaces of the box walls.

Thereafter, the wrapped box moves slightly downwardly to a position where pressure may be applied to the wrapper sections aforesaid freshly folded into engagement with the interior surfaces of the box walls. The wrapped box and a part of the associated pressure-applying mechanism is illustrated in Fig. 15, wherein a box-squaring or presser block 95 is supported in a housing 96 in turn supported in a member 97 from which rises a bearing 98 slidably supporting a rod or plunger 99 on whose stem is mounted a coil spring 100 or the like for biasing said plunger toward the right, as viewed in Fig. 15, to the extent permitted by the adjustment of nuts 101 on the threaded end of the plunger stem. Member 97 is

also apertured, as indicated at 102, for the reception of the turn-in finger structure described above. Presser block 95 comprises a stem 103 slidably mounted in aligned apertures in the members 96 and 97 for actuation in succession by the high points 104 and 105 of cam 85.

When the form block structures had positioned the partially wrapped box for action by the turn-in finger structure, the point 104 of cam 85 became effective to apply light pressure to the walls of the box. However, when the wrapped box is in its lowermost position, after retraction of the turn-in finger structure aforesaid, the point 105 of cam 85, which is higher than point 104, co-acts with stem 103 for applying a substantial amount of pressure to the exterior box wall. Due to the action of high point 105 on stem 103, member 97 is moved toward the right, Fig. 15, and stem 99 engaged with lug 51 on presser member 50 to thereby apply pressure to the wrapper surface just folded into engagement with the interior top surface of the box wall, whereby such wrapper surface is caused to remain in intimate contact with the adjacent surface of the box wall structure.

It shall be understood that mechanism of the character just described is mounted adjacent each wall of the box whereby in the last stage of the wrapping operation all of the turn-in sections freshly folded into engagement with the upper interior surfaces of the box walls are gripped and squeezed between a presser member, as member 50, and a box-squaring or presser block, as member 95.

At the conclusion of the operation aforesaid, the form block structure immediately transports the wrapped box upwardly without pause until fingers 34 function to strip the box from said form block structure. As well understood in the art, all of the various tools and instrumentalities have been withdrawn from the path of the form block structure to permit such upward movement.

In Fig. 12, there is illustrated with significant legends the cam slots G¹, G², G³ and G⁴. The line G¹ indicates cam groove G¹ of cam 6, and shows the timing of the stripper-operating mechanism comprising the strippers 34. Line G² indicates cam slot G² of cam 6, and shows the timing of the intermediate form block structure 22. Line G³ indicates the cam groove G³ in cam 8, and shows the timing of the corner-lap plates 68. Line G⁴ indicates the cam groove G⁴ in cam 8, and shows the timing of the turn-in plates or fingers 88 and 93.

In this specification and in the appended claims, for the sake of clarity it has been arbitrarily assumed that the box B comprises the bottom B¹, end walls B², front

wall B³ and rear wall B⁴. It has also been assumed that the box always occupies a normal position, namely, one wherein the so-called bottom B¹ is lowermost. It shall be understood that this apparent limitation has been introduced into the specification and claims merely for the sake of clearness, and that my invention is not to be restricted by this choice of language.

What I claim is:

1. In the art of applying a wrapper to a box, the upper horizontal surface of whose wall structure occupies different levels in different portions thereof, the method which comprises folding a portion of the wrapper into engagement with the horizontal surface of the box wall structure in one level thereof, slitting the wrapper in a direction extending toward a lower horizontal level of said wall structure, and thereafter folding another portion of the wrapper into engagement with a lower horizontal level of the wall structure.

2. In the art of applying a wrapper to a box, the upper horizontal surface of whose wall structure occupies different levels in different portions thereof, the method which comprises folding a portion of the wrapper into engagement with the horizontal surface of the box wall structure in one level thereof and simultaneously slitting the wrapper in a direction extending toward a lower horizontal level of said wall structure, and thereafter folding another portion of the wrapper into engagement with a lower horizontal level of the wall structure.

3. In the art of applying a wrapper to a box having a side and end wall meeting in a corner, the method which comprises effecting engagement between the bottom of the box and a section of the wrapper, applying a wrapper side panel to a box side wall, folding a portion of said side panel into engagement with the horizontal surface of a box end wall, applying a wrapper end panel to said box end wall, and folding a portion of said end panel into engagement with the horizontal surface of said box end wall.

4. In the art of applying a wrapper to a box having a side and end wall meeting in a corner, the method which comprises effecting engagement between the bottom of the box and a section of the wrapper, applying a wrapper side panel to a box side wall, folding a portion of said side panel into engagement with the horizontal surface of a box end wall, folding a corner-lap section comprised in said side panel into engagement with the vertical surface of said box end wall, applying a wrapper end panel to said box end wall, and folding a portion of said end panel into engagement with the horizontal surface of said box end wall.

5. In the art of applying a wrapper to a box having a side and end wall meeting in

5 a corner, the method which comprises effecting engagement between the bottom of the box and a section of the wrapper, applying a wrapper side panel to a box side wall, folding a portion of said side panel into engagement with the horizontal surface of a box end wall, folding a corner-lap section comprised in said side panel into engagement with the vertical surface of said box end 10 wall, applying a wrapper end panel to said box end wall, and folding a portion of said wrapper end panel and a portion of said corner-lap section into engagement with the horizontal surface of said box end wall.

15 6. In the art of applying a wrapper to a box having a side and end wall meeting in a corner, the method which comprises effecting engagement between the bottom of the box and a section of the wrapper, applying 20 a wrapper side panel to a box side wall, and, as a substantially simultaneous operation, folding a portion of said side panel into engagement with the horizontal surface of a box end wall, folding a portion of a corner-lap section comprised in said panel into engagement with the vertical surface of said box end wall, and creasing another portion of said corner-lap section whereby the extremity thereof extends substantially vertically 25 above said end wall.

7. In the art of applying a wrapper to a box having a side and end wall meeting in a corner, the method which comprises effecting engagement between the bottom of the 30 box and a section of the wrapper, applying a wrapper side panel to a box side wall, and, as a substantially simultaneous operation, folding a portion of said side panel into engagement with the horizontal surface of a box end wall, folding a portion of a corner-lap section comprised in said panel into engagement with the vertical surface of said box end wall, creasing another portion of 35 said corner-lap section whereby the extremity thereof extends substantially vertically above said end wall, applying a wrapper end panel to said box end wall, and folding a portion of said wrapper end panel and the upstanding portion of said corner-lap section 40 into engagement with the horizontal surface of said box end wall.

45 8. In the art of applying a wrapper to a box having a side and end wall meeting in a corner and which rise, respectively, different distances from the box bottom, the method which comprises effecting engagement between the bottom of the box and a section of the wrapper, applying a wrapper side panel to a box side wall, folding a portion 50 of said wrapper side panel into engagement with the horizontal surface of a box end wall, and folding another portion of said wrapper side panel into engagement with said side wall.

55 9. In the art of applying a wrapper to

a box having a side and end wall meeting in a corner and which rise, respectively, different distances from the box bottom, the method which comprises effecting engagement between the bottom of the box and a section of the wrapper, applying a wrapper side panel to a box side wall, folding a portion of said wrapper side panel into engagement with the horizontal surface of a box end wall, slitting said wrapper side 70 panel in a direction extending towards said side wall, and folding another portion of said wrapper side panel into engagement with said side wall.

10. In the art of applying a wrapper to a box having a side and end wall meeting in a corner and which rise, respectively, different distances from the box bottom, the method which comprises effecting engagement between the bottom of the box and a section of the wrapper, applying a wrapper side panel to a box side wall, and, as a substantially simultaneous operation, folding a portion of said wrapper side panel into engagement with the horizontal surface of a box end wall, folding a portion of a corner-lap section comprised in said wrapper side panel into engagement with the vertical surface of said box end wall, creasing another portion of said corner-lap section, and slitting 90 said wrapper side panel in a direction extending towards said side wall.

11. In the art of applying a wrapper to a box, two of whose walls meet in a corner and which rise, respectively, different distances from the box bottom, the method which comprises effecting engagement between the bottom of the box and a portion of the wrapper, folding a portion of a wrapper panel into engagement with a box wall, folding another portion of said panel into engagement with the horizontal surface of another box wall rising a greater distance from the box bottom than does said first mentioned box wall, slitting the panel in a direction extending toward said first mentioned box wall, and folding another portion of the panel into engagement with the horizontal surface of said first mentioned box wall.

12. In the art of applying a wrapper to a box two of whose walls meet in a corner and which rise, respectively, different distances from the box bottom, the method which comprises effecting engagement between the bottom of the box and a portion of the wrapper, folding a portion of a wrapper panel into engagement with a box wall, folding another portion of said panel into engagement with the horizontal surface of another box wall rising a greater distance from the box bottom than does said first mentioned box wall and simultaneously slitting the panel in a direction extending toward said first mentioned box wall, and

thereafter folding another portion of the panel into engagement with the horizontal surface of said first mentioned box wall.

13. In the art of applying a wrapper to a box, the method which comprises effecting engagement between the bottom of the box and a portion of the wrapper, folding a panel of the wrapper into engagement with a box wall, folding a corner-lap section comprised in said panel into engagement with a box wall rising a different distance from the box bottom than does said first mentioned box wall but meeting therewith to form a box corner, and folding a portion of said panel into engagement with the horizontal surface of said second mentioned box wall.

14. In the art of applying a wrapper to a box, the method which comprises effecting engagement between the bottom of the box and a portion of the wrapper, folding a panel of the wrapper into engagement with a box wall, folding a corner-lap section comprised in said panel into engagement with a box wall rising a different distance from the box bottom than does said first mentioned box wall but meeting therewith to form a box corner, folding a portion of said panel into engagement with the horizontal surface of said second mentioned box wall, and creasing the extremity of said corner-lap section to form an upstanding wrapper section.

15. In the art of applying an adhesive coated wrapper to a box, the method which comprises effecting engagement between the bottom of the box and a section of the wrapper, folding a wrapper panel into engagement with a box wall, moving a surface transversely of said box wall to simultaneously fold a portion of the turn-in section of said panel into engagement with a horizontal surface of said box wall and apply pressure to said panel portion to secure it to said horizontal surface.

16. In the art of applying an adhesive coated wrapper to a box, the method which comprises effecting engagement between the bottom of the box and a section of the wrapper, folding a wrapper panel into engagement with a box wall, and moving a surface transversely of said box wall to simultaneously fold a portion of the turn-in section of said panel into engagement with a horizontal surface of said box wall while applying pressure to said panel portion to secure it to said horizontal surface.

17. In a wrapping machine, form block structure for carrying a box having a wrapper adhering to the box bottom along a predetermined path, means for folding a wrapper panel into engagement with a box wall, and means for folding a corner-lap section of said panel into engagement with a box wall meeting said first mentioned box wall in a corner comprising structure for slitting

said panel in a direction extending toward the box bottom and for folding a portion of said panel into engagement with the horizontal surface of said second mentioned box wall.

18. In a wrapping machine, form block structure for carrying a box having a wrapper adhering to the box-bottom along a predetermined path, means for folding a wrapper panel into engagement with a box wall, and means for folding a corner-lap section of said panel into engagement with a box wall meeting said first mentioned box wall in a corner comprising structure for slitting said panel in a direction extending toward the box bottom.

19. In a wrapping machine, form block structure for carrying a box having a wrapper adhering to the box-bottom along a predetermined path, means for folding a wrapper panel into engagement with a box wall, and means for folding a corner-lap section of said panel into engagement with a box wall meeting said first mentioned box wall in a corner comprising structure for folding a portion of said panel into engagement with the horizontal surface of said second mentioned box wall.

20. In a wrapping machine, form block structure for carrying a box having a wrapper adhering to the box bottom along a predetermined path, means for applying the wrapper panels to the walls of the box on their exterior surfaces, and means for folding a wrapper turn-in section inwardly comprising a member movable transversely of said path and biased toward the upper horizontal surface of a box wall.

21. In a wrapping machine, form block structure for carrying a box having a wrapper adhering to the box bottom along a predetermined path, means for applying the wrapper panels to the walls of the box on their exterior surfaces, means for folding a wrapper turn-in section inwardly comprising a pivotally mounted member movable transversely of said path, and means for biasing said member toward the upper horizontal surface of a box wall.

22. In a wrapping machine, form block structure for carrying a box having a wrapper adhering to the box bottom along a predetermined path, means for applying the wrapper panels to the walls of the box on their exterior surfaces, and means for folding a wrapper turn-in section inwardly into adhering relation with the upper horizontal surface of a box wall comprising a plurality of plate-like members movable transversely of said path and biased toward the upper horizontal surface of said wall.

23. In a wrapping machine, form block structure for carrying a box having a wrapper adhering to the box-bottom along a predetermined path, means for causing the

- wrapper panels to engage the exterior walls of the box, and means for folding a wrapper turn-in section inwardly comprising a structure movable in timed relation with the form block structure and relatively movable members carried by said movable structure, one of which is adapted to support the upper form block. 70
24. In a wrapping machine, form block structure for carrying a box having a wrapper adhering to the box-bottom along a pre-determined path, means for causing the wrapper panels to engage the exterior walls of the box, and means for folding a wrapper turn-in section inwardly comprising a structure movable in timed relation with the form block structure and relatively movable members carried by said movable structure and adapted, respectively, for supporting the upper form block and for wiping the wrapper turn-in section into engagement with the top horizontal surface of the box wall. 80
25. In a wrapping machine, form block structure for carrying a box having a wrapper adhering to the box-bottom along a pre-determined path, means for causing the wrapper panels to engage the exterior walls of the box, and means for folding a wrapper turn-in section inwardly comprising a structure movable in timed relation with the form block structure, a member secured to said movable structure adapted to support the upper form block, a plurality of plate-like members pivoted to said movable structure, and means for biasing said plate-like members toward the top horizontal surface of the box wall. 90
26. In a wrapping machine, form block structure for carrying a box having a wrapper adhering to the box-bottom along a pre-determined path, means for first folding the wrapper panels into engagement with the exterior surfaces of the box walls and thereafter into engagement with the interior surfaces thereof, means comprised in said form block structure for applying pressure to a box wall, and means independent of said form block structure for actuating said last named means. 95
27. In a wrapping machine, form block structure for carrying a box having a wrapper adhering to the box-bottom along a pre-determined path, means for first folding the wrapper panels into engagement with the exterior surfaces of the box walls and thereafter into engagement with the interior surfaces thereof, plate-like members carried by the upper form block for applying pressure to a box wall, and means independent of said form block structure for actuating said members. 100
28. In a wrapping machine, form block structure for carrying a box having a wrapper adhering to the box-bottom along a pre-determined path, means for first folding the wrapper panels into engagement with the exterior surfaces of the box walls and thereafter into engagement with the interior surfaces thereof, means comprised in said form block structure for applying pressure to a box wall, and means timed with said form block structure for actuating said last-mentioned means. 105
29. In a wrapping machine, form block structure for carrying a box having a wrapper adhering to the box-bottom along a pre-determined path, means for first folding the wrapper panels into engagement with the exterior surfaces of the box walls and thereafter into engagement with the interior surfaces thereof, means comprised in said form block structure for applying pressure to a box wall, means timed with said form block structure for actuating said last mentioned means and for simultaneously applying pressure to the exterior surface of said box wall. 110
30. In a wrapping machine, form block structure for carrying a box having a wrapper adhering to the box-bottom along a pre-determined path, means for first folding the wrapper panel into engagement with the exterior surfaces of the box walls and thereafter into engagement with the interior surfaces thereof, a plate-like member pivoted to said upper form block for applying pressure to the interior surface of the box wall, and present-applying structure movable in timed relation with the form block structure into engagement with the exterior surface of said box wall and comprising a member for actuating said pivotally mounted plate-like member. 115
31. A corner-lap turn-in member for wrapping machine comprising means for slitting a wrapper. 120
32. A corner-lap turn-in member for a wrapping machine comprising means for folding a portion of the wrapper into engagement with the top horizontal surface of the box wall. 125
33. A corner-lap turn-in member for a wrapping machine comprising means for simultaneously slitting a wrapper and folding a portion thereof into engagement with the top horizontal surface of the box wall. 130
34. A corner-lap turn-in member for a wrapping machine comprising a resiliently mounted knife edge. 135
35. A corner-lap turn-in member for a wrapping machine comprising a knife edge mounted on a resilient presser bar. 140
36. A substantially rectangular, reciprocating upper form block adapted to be passed interiorly, of a box, and a pivoted member forming with said form block a structure whose cross sectional area while without the box and transversely of its path of movement is no greater than the interior cross sectional area of the box. 145
37. A reciprocating upper form block 150

adapted to be passed interiorly of a box, and a movable member comprising an up-standing actuating part forming with said form block a structure whose cross sectional area while without the box and transversely of its path of movement is no greater than the interior cross sectional area of the box.

38. An upper form block adapted to be passed interiorly of a box and comprising a recessed box-engaging face, and a pivoted member lying within said recessed face when said form block is without the box.

39. Wrapping machine turn-in structure for folding portions of a wrapper over a box wall comprising a member biased toward the

top horizontal surface of said wall and movable transversely of the path of the box.

40. Wrapping machine turn-in structure for folding portions of a wrapper over a box wall comprising a pivotally mounted plate-like member biased toward the top horizontal surface of said wall and movable transversely of the path of the box. 20

41. Wrapping machine turn-in structure for folding portions of a wrapper over a box wall comprising a plurality of plate-like members biased toward the top horizontal surface of said wall and movable transversely of the path of the box. 25

JOHN R. SONNEBORN.

adapted to be passed interiorly of a box, and a movable member comprising an up-standing actuating part forming with said form block a structure whose cross sectional area while without the box and transversely of its path of movement is no greater than the interior cross sectional area of the box.

38. An upper form block adapted to be passed interiorly of a box and comprising a recessed box-engaging face, and a pivoted member lying within said recessed face when said form block is without the box.

39. Wrapping machine turn-in structure for folding portions of a wrapper over a box wall comprising a member biased toward the

top horizontal surface of said wall and movable transversely of the path of the box.

40. Wrapping machine turn-in structure for folding portions of a wrapper over a box wall comprising a pivotally mounted plate-like member biased toward the top horizontal surface of said wall and movable transversely of the path of the box.

41. Wrapping machine turn-in structure for folding portions of a wrapper over a box wall comprising a plurality of plate-like members biased toward the top horizontal surface of said wall and movable transversely of the path of the box.

JOHN R. SONNEBORN.

Patent No. 1,646,563.

Certificate of Correction.

Granted October 25, 1927, to

JOHN R. SONNEBORN.

It is hereby certified that error appears in the above-numbered patent requiring correction as follows: In the drawing, Figure 14, for the reference character "87" read 86; page 3, line 21, of the printed specification for the word "or" read *of*; page 4, line 54, for the word "its" read *is*; same page, line 120, for the word "grooves" read *groove*; page 5, line 112, for the compound word "corner-lamp" read *corner-lap*; page 6, line 73, for the word "spring" read *springs*; page 10, line 97, claim 30, for the compound word "present-applying" read *pressure-applying*; same page, line 103, claim 31, after the word "for" insert the article *a*; and line 124, claim 36, after the word "interiorly" strike out the comma; and that the said Letters Patent should be read with these corrections therein that the same may conform to the record of the case in the Patent Office.

Signed and sealed this 17th day of January, A. D. 1928.

[SEAL.]

M. J. MOORE,
Acting Commissioner of Patents.

DISCLAIMER

1,646,563.—John R. Sonneborn, Willow Grove, Pa. Box-WRAPPING SYSTEM. Patent dated October 25, 1927. Disclaimer filed September 18, 1934, by the assignee, Autokraft Box Corporation.

Hereby enters this disclaimer, to wit:

"1. Your petitioner hereby disclaims from the scope of each of claims 3, 4, 5, 8, 13, and 14, any method of applying a wrapper except to a box wherein the side walls thereof are of less height than the end walls thereof;

"2. Your petitioner hereby disclaims from the scope of each of claims 3, 4, 5, 8, 13, and 14, any method of applying a wrapper except a method wherein the portion of the side panel which is folded into engagement with the horizontal surface of a box end wall is not included within a corner-lap section, and is folded into engagement with the horizontal surface of the end wall in the direction of the length of that wall."

[Official Gazette October 16, 1934.]

DISCLAIMER

1,646,563.—*John R. Sonneborn*, Willow Grove, Pa. BOX-WRAPPING SYSTEM. Patent dated October 25, 1927. Disclaimer filed April 2, 1938, by the assignee, *Autokraft Box Corporation*.

Hereby enters this disclaimer to claims 15 and 16 of said patent.
